UNITED STATES PATENT OFFICE.

FREDERIC H. BATEMAN, OF GRENLLOCH, NEW JERSEY, ASSIGNOR TO BATEMAN MANUFACTURING COMPANY, OF GRENLLOCH, NEW JERSEY, A CORPORATION OF NEW JERSEY.

ADJUSTABLE MOUNTING FOR PLOWS.

1,294,860.

Specification of Letters Patent. Patented Feb. 18, 1919.

Application filed October 7, 1918. Serial No. 257,172.

To all whom it may concern:

Be it known that I, FREDERIC H. BATEMAN, a citizen of the United States, residing in Grenloch, New Jersey, have invented 5 certain Improvements in Adjustable Mountings for Plows, of which the following is a specification.

The invention relates to plows, and particularly to the method in which the plow-share is mounted upon the frame, the object of my invention being to so construct the mounting that the plow-share may be adjusted in respect to the frame so as to cause it to point downwardly and serve as a digging plow or to point forwardly and serve as a covering plow.

This object I attain in the manner herein-after set forth, reference being had to the accompanying drawing, in which—

20 Figure 1 is a side view of a plow-share with mounting constructed in accordance with my invention, the plow-share being adjusted to serve as a digging plow;

25 Fig. 2 is a similar view with the plow-share so adjusted as to serve as a covering plow;

Fig. 3 is an enlarged sectional view of the mounting in the position shown in Fig. 1, and

30 Fig. 4 is a view similar to Fig. 3 but with the parts in the position shown in Fig. 2.

In the drawing, the frame 1 of the plow is shown as provided with a slotted transverse bearing member 2 through which 35 passes a retaining bolt 3. This bolt also passes through a slotted head 4 on the plow standard 5 and is provided with a head 3^a whose upper convex face coöperates with the concave lower face 4^x of the head 4. This 40 construction enables the bolt 3 to always exert a vertical pull upon the head 4 irrespective of the angular position occupied by said head in respect to the bearing member 2 of the frame.

45 Depending from the head 4 is the plow standard 5, to the lower end of which is secured the curved plowshare 6. The position of the plowshare is controlled by the relation of the head 4 with respect to bearing member 2 and in order to provide different 50 relative positions between the same, the upper face of said head has formed on it a pair of forwardly facing shoulders 4^a and 4^b

and a pair of rearwardly facing shoulders 4^c and 4^d. When it is desired to have the 55 plow-share serve as a digging plow, it is adjusted as shown in Fig. 1, pointing downwardly. When adjusted to this position the shoulder 4^a of the head 4 engages the forward wall of the slot in the bearing member 60 65 and the shoulder 4^d engages the rear wall of the same, as shown in Fig. 3, and tightening of the nut on the bolt 3 holds the parts rigidly in engagement. When it is desired to have the plowshare serve as a 70 covering plow it is adjusted as shown in Fig. 2, pointing ahead. In this case, the shoulder 4^b engages the front wall of the slot in the bearing member 2, and the shoulder 4^c engages the rear wall of the same. As 75 will be seen, the required adjustment may be easily and quickly effected and the parts, when adjusted, are securely retained in their proper positions.

Although I have shown and described my 75 invention in connection with plows, for which use it was devised and to which it is particularly adapted, I do not limit myself to this use, as the same type of connection may be used in connection with other 80 ground-working tools, such as spike-teeth, cultivator blades, etc., in case it should be desired to use such tools in different angular positions. The claims will, therefore, be 85 read with this understanding.

I claim:

1. The combination, in an agricultural implement, of a slotted bearing member, a securing head, a plow carried by said head, a pair of forwardly facing shoulders and a 90 pair of rearwardly facing shoulders on said head, and means for retaining the head in either of two positions, in one of which positions one shoulder of one pair is in engagement with the front wall of the slot in the bearing member and one shoulder of the other pair is in engagement with the rear wall of said slot, and in the other of which positions the other shoulder of each pair is in 95 such engaging relation.

2. The combination, in an agricultural implement, of a slotted bearing member, a slotted securing head, a plow carried by said head, and a retaining bolt passing through the slots in said head and bearing 100 member, and serving to secure the same to 105

gether, said bolt having a head with convex upper face, and said securing head having a concave lower face adapted to be engaged by the convex-faced head on said bolt where-
5 by a straight pull is always exercised upon said securing head by said bolt irrespective

of the angular adjustment existing between said securing head and said frame.

In testimony whereof, I have signed my name to this specification.

FREDERIC H. BATEMAN.
